[57] **CLAIM**

The ornamental design for an IC card, as shown.

DESCRIPTION

FIG. 1 is a front, bottom and right side perspective view of an IC card, showing my new design;

FIG. 2 is a top plan view thereof;

FIG. 3 is a right side elevational view thereof;

FIG. 4 is a front elevational view thereof;

FIG. 5 is a bottom plan view thereof;

FIG. 6 is a left side elevational view thereof; and,

FIG. 7 is a rear elevational view thereof.
